ABSTRACT OF THE DISCLOSURE

An air eliminator and vacuum breaker employing flexible reed type valves actuated by a float which moves the reeds against and away from associated valve seats as the level of liquid moves up and down in a float chamber. Each reed is connected to the float on the opposite side of the float from the seat portion to which the respective reed is secured.

The present invention relates in general to fluid control devices, and it relates more particularly to a combination air eliminator and vacuum breaker which is well suited for use in water supply systems.

In water supply systems of the pressurized type, water is transmitted under pressure from a reservoir or pumping station to various locations where it is ultimately used. Underground pipes are commonly used to carry the water from the reservoir or pumping station to the user and it is important that such pipes be completely full of water, i.e., free from air. Since the commonly used water pipe is unable to withstand a high vacuum, it is also important that the pressure within the pipe be approximately atmospheric or greater. In the past, these two different objectionable conditions have been avoided by two separate pieces of equipment, an air eliminator and a vacuum breaker, and a multiplicity of these devices are used in a typical water supply system. Air being less dense than water tends to rise to the high points in the system and it is also at the high points where the occurrence of a vacuum would be most destructive. Consequently, because of the fact that they are both needed at the high elevation points of the system, an air eliminator and a vacuum breaker are usually located side-by-side.

Although combination air eliminators and vacuum breakers have not heretofore been used in water supply systems, there is a type of air eliminator widely used in the petroleum industry which is also capable of use as a vacuum breaker. This type of air eliminator employs a plurality of flexible reeds which are connected to a float which moves the reeds against and away from associated valve seats as the level of liquid moves up and down in a float chamber. The flexibility of the reeds may be such that when the pressure in the float chamber is less than the downstream pressure across the valve seat by a predetermined amount, the reed is forced away from the seat to open the valve and equalize the pressures. Several air eliminators of this general type are disclosed in United States Letters Patents 3,021,861 granted Feb. 20, 1962 to H. R. Billeter and G. B. Richards; 3,131,709 granted May 5, 1964 to G. B. Richards; 3,154,091 granted Oct.

2

27, 1964 to G. B. Richards, et al.; 3,230,965 granted June 25, 1966 to G. B. Richards; and 3,230,966 granted June 25, 1966 to G. B. Richards.

While the air eliminators disclosed in the above-identified patents could be used in water systems, because of the high pressures and volumes to be handled, the devices would have to be relatively large and it would, therefore, be desirable to provide a combination air eliminator and vacuum breaker which would be smaller or less massive than these prior art devices.

Hence, the principal object of the present invention is to provide an improved air eliminator construction suitable for use in a high pressure, high volume, liquid supply system.

Another object of this invention is to provide a new and improved combination air eliminator and vacuum breaker.

A further object of this invention is to provide a combination air eliminator and vacuum breaker which is suitable for use in a community or industrial type water supply system and which is sturdy in construction, compact in size and both efficient and reliable in operation.

Briefly, the above and further objects are realized in accordance with the present invention by providing a reed type air eliminator in which the convolutions of the reeds are increased by one-hundred percent over those of the prior art eliminators without any appreciable increase in the overall size of the device. As a result, the reeds may be heavier and stronger to handle greater pressures and to permit the use of larger valve ports. It will be understood that this construction can also be used in systems handling lower pressures and volumes and in such cases the reeds may be the same weight as those used in the prior art eliminators but the overall size of the unit can be substantially reduced.

The invention, both as to its organization and method of operation, together with further objects and advantages thereof, will best be understood by reference to the following detailed description taken in connection with the accompanying drawings, in which:

FIGURE 1 is a sectional view of a combined air eliminator and vacuum braker embodying certain features of the present invention;

FIGURE 2 is a top view of the device of FIG. 1 with the cover removed;

FIGURE 3 is a side elevational view of the portion of FIG. 1 including the outlet port;

FIGURE 4 is a front elevational view of the float assembly used in the device of FIG. 1;

FIGURE 5 is a top view of the float assembly of FIG. 4;

FIGURE 6 is a side elevational view, reduced in size, of the float assembly of FIGS. 4 and 5;

FIGURE 7 is a front elevational view of the valve seat and reed support used in the device of FIG. 1;

FIGURE 8 is a side elevational view of the valve seat and reed support of FIG. 7;

FIGURE 9 is a top view of the valve seat and reed support of FIGS. 7 and 8;

FIGURE 10 is a front elevational view of the reed support used in the device of FIG. 1;

FIGURE 11 is a side elevational view of the reed support shown in FIG. 10;

FIGURE 12 is a top view of the reed support shown in FIGS. 10 and 11;

FIGURE 13 is a sectional view of another combined air eliminator and vacuum breaker embodying the present invention; and

FIGURE 14 is a top view of the device of FIG. 13 with the cover removed.

Referring now to the drawings, and more particularly to FIGS. 1 and 2 thereof, there is shown a combined air eliminator and vacuum breaker valve 20 which includes a cover member 22 sealably secured over the top of a main housing member 24. The members 22 and 24 may be castings having respective flanges 26 and 28 provided with a plurality of aligned holes 30 for receiving mounting bolts, not shown. A suitable O-ring gasket 32 is mounted in an annular recess at the top of the housing member 24 to provide a seal between the housing 24 and the cover member 22.

Water or other liquid may be supplied to and from the float chamber within the housing 24 through a port 34 provided at the bottom of the housing 24. The opening 34 is tapped to receive a conventional plumbing nipple for connecting the device 20 into the system. A drain port 36 is provided near the bottom of the housing 24 and is also tapped for receiving a suitable plumbing nipple or plug (not shown).

Inspection and testing of the operation of the device 20 is facilitated by means of an opening 38 provided in the cover member 22. As shown, the opening is tapped for receiving a plumbing nipple or a plug.

A plurality of bosses 40 which form an integral part of the housing 24 extend inwardly from the inner wall thereof about the periphery of the inlet port 34 and provide a means for preventing a hollow, spherical float 42 from seating directly on the bottom of the float chamber and blocking the port 34.

Referring also to FIGS. 4 and 5, it may be seen that the float 42 is secured to and forms a part of a float assembly 44. Suitably secured to the float 42 such as by means of a weld 46 is a float stop member 48 which is generally box-shaped and may be formed from a single sheet of metal. The float stop member 48 includes a pair of off-turned, horizontally disposed stop flanges 50 and 52 which are adapted to be disposed in a common horizontal plane when the eliminator 20 is in a vertical position. As is more fully described hereinafter, these flanges 50 and 52 cooperate with other elements in the device to limit the upward movement of the float assembly 44. The stop member 48 further includes vertical side wall portions 54, 56, 58 and 60 with the oppositely disposed end walls 56 and 60 being spaced apart by a dimension equal to the diameter of the ball 42. The side walls 54 and 58 depend to a position where they engage the surface of the ball 42 and may be suitably welded to the ball at the positions of engagement. For ease of manufacture, the marginal edge 62 of the wall 60 is welded to the adjacent corner of the side wall 54. Supporting surfaces for a pair of balancing reeds 100 and 102 are provided by a pair of vertical flanges 63 and 65 at the marginal edges of the side walls 54 and 58.

An air outlet port 64 is provided by a hole in the wall of the housing member 24 near the top thereof and is suitably tapped for receiving a plumbing nipple which may be connected to the atmosphere. A valve seat assembly 66, shown in detail in FIGS. 7, 8 and 9, is secured to the inner wall of the housing 24 by means of a pair of machine screws 68 and 70 extending through counterbores in the housing member 24 above and below the port 64. As shown, the assembly 66 includes a pair of elongated ports 72 and 74 aligned with the opening 64.

In order to resist corrosion and to provide a resilient seat for the valve member, the valve seat assembly 66 is preferably formed of stainless steel which is partially covered with a suitable resilient material such as Buna N to provide a resilient valve seat surface and to provide a seal around the port 64. The lower end of the metal portion of the assembly 66, which is identified in the

drawings by the numeral 76, is uncoated and is off-turned to provide a mounting tab for an associated reedlike valve member 78. The valve member 78 is flexible and in order to prevent its being deformed at the location of the valve seat, the separate ports 72 and 74 are provided and separated by an intermediate wall member 80. Moreover, the valve seat area is constituted by a plurality of raised rib-like portions 82, thereby providing a minimum seating area.

The flexible reed 78, which functions as a valve member, is apertured at its lower end and is secured to the tab 76 by means of a machine screw 84 which extends through the hole in the reed and is threaded into an aperture 86 in the tab 76. The reed 78 extends up over the top of the stop member 48 and back down into the space between the walls thereof to provide a convolution. The opposite end of the reed is connected to the inside of the wall 56 by means of a screw 88 which extends through an aperture 90 in the wall 56, through an aperture in the reed and into a nut 92. The reed 78 has a width sufficient to overlie the valve opening 72 and 74 in the valve seat assembly 66 and is located along a diameter of the eliminator. The offset of the tab 76 causes the reed 78 to be biased against the valve seat to insure that the valve closes tightly when the float assembly moves into the valve closing position.

In order to equalize the transverse forces on the float assembly so that it will move only in a vertical direction, as the level of liquid in the housing member 24 varies, a pair of reeds 100 and 102 are respectively fastened to the pair of off-turned flanges 63 and 65 on the stop member 48 by means of nut and bolt assemblies 108 and 110. The opposite ends of the reeds 100 and 102 are fastened by means of nut and bolt assemblies 112 and 114 to a reed support bracket 116 secured to the side of the housing 24 directly opposite to the port 64. The bracket 116 is best shown in FIGS. 10, 11 and 12. As shown, the reed support member 116 has a central web portion 118 provided with a pair of threaded apertures 120 and 122 for receiving mounting screws 124 which extend through counterbores in the side of the housing member 24. The lower end of the bracket 116 is provided with a pair of struck-out off-turned tabs 126 and 128 which are apertured to receive the nut and bolt assemblies 112 and 114, respectively. Inasmuch as the bracket 116 is merely a fixed support for the reeds, it need not be coated with a resilient material as is the preferred embodiment of the valve seat member 66.

Inasmuch as the reeds 100 and 102 exert a force toward the right, as viewed in FIG. 1, on the float assembly 44, the purpose of which is to counterbalance the force exerted to the left by the reed 78, the combined effect of the reeds 100 and 102 must be equal to the effect of the single reed 78. Accordingly, where the reeds are all of the same thickness and formed of the same material, it will be apparent that the reed 78 should have a width twice as great as each of the reeds 100 and 102 which are of equal width.

Operation

When the combined air eliminator and vacuum breaker 20 is connected into a system, the port 38 will normally be plugged or connected to a valved inspection line in which the valve is normally closed. The port 64 will be connected to the atmosphere and the port 34 will be connected to the water line whereby water flows into the float chamber through the inlet port 34. In the absence of air in the system, the chamber within the housing 24 will be substantially filled with water whereby the float assembly occupies the uppermost position (shown in FIG. 1) as determined by the stop flanges 50 and 52 seating on the lower edges of the valve seat assembly 66 and the reed support bracket 116. In this position the reed 78 seats against the valve seat thereby closing the ports 72 and 74. As explained hereinbefore, the air eliminator 20 will normally be located at a high point in the system so

that any air in the system will collect in the upper part of the air eliminator housing thus decreasing the level of liquid in the float chamber with the result that the float assembly 44 will fall under the force of gravity toward the bottom of the housing 74 whereby the reed 78 is moved away from the valve seat to open the ports 72 and 74 whereby the upper portion of the float chamber is opened to the atmosphere. The air collected at the top of the eliminator will thus be forced out of the system by the water moving upwardly in the float chamber until the stop flanges 50 and 52 again seat against the bottoms of the members 66 and 116 and the valve ports 72 and 74 are closed by the reed 78.

Should the pressure within the chamber 24 decrease below atmospheric pressure, an inwardly directed force will be exerted against the reed 78 forcing it away from the valve seat and thereby breaking the vacuum in the system. The degree of flexibility of the reed 78 should thus be selected such that it will be moved away from the valve seat at a pressure differential less than that which would collapse the pipes or damage other equipment in the remainder of the system.

Referring to FIGS. 13 and 14, there is shown another embodiment of the present invention. As there shown, a combined air eliminator and vacuum breaker 130 includes a housing 132 defining a float chamber over the top of which is sealably connected a cover member 134. The cover 134 and the housing 132 having mating flanges 136 and 138, respectively, which are provided within aligned apertures for receiving a plurality of fastening bolts 140. A test opening 142 is provided at the center of the cover 134 and is threaded at the upper portion 144 for receiving a plug 146 or a suitable plumbing nipple. The opening 142 is provided at the bottom with a thread 147 for receiving a bushing 150.

In this embodiment of the invention a unitary member 148, which may be molded of a suitable plastic, such, for example, as Delrin sold by E. I. du Pont de Nemours Corporation of Wilmington, Del., includes a circular plate portion 149 having a peripheral annular flange 152 which is secured between the cover 134 and the mating portion of the housing 132. An O-ring gasket 154 is received in a suitable groove at the top of the housing member 132 for sealing the float chamber from the atmosphere.

A tubular air outlet section 156 depends from the plate portion 149 in line with a threaded opening 158 in the cover 134 and is provided near its lower end with an aperture 160 facing toward the center line of the housing member 132. A resilient washer 162 is suitably secured to the tubular portion 156 by means of a pair of countersunk machine screws 164 and provides a valve seat surrounding the opening 160. The lower end of the tube 156 extending below the washer 162 is provided with an off-turned face 166 to which the lower end of a flexible reed member 168 is secured by means of a screw 170. The opposite end of the reed 168 is secured by a bolt and nut assembly 172 to a plate-like bracket 174 which is welded to a ball float member 176 directly opposite to the valve seat washer 162. A pair of counter-balancing reeds 178 and 180 are respectively connected on opposite sides of the reed 168 to an upstanding plate-like bracket 182 which is suitably welded to the ball float 176 and are connected at their opposite ends by means of a pair of screws 184 and 186 to an arm 188 which depends from the flange 152. The reeds 178 and 180, which lie in planes parallel to that of the reed 168 have a combined width equal to the width of the valve reed 168 whereby the opposing transverse forces on the ball float assembly are balanced out.

In operation, the combined air eliminator and vacuum breaker 130 operates in the same manner as does the air eliminator and vacuum breaker 20.

It may thus be seen that the present invention provides an air eliminator construction in which the diameter of the float chamber is not substantially greater than 75

that of the float but the reeds have convolutions exceeding the diameter of the float and approximately that of the float chamber. A more compact unit is thus provided which enables the handling of the relatively high pressures encountered in water supply systems and the like.

While the present invention has been described by means of particular embodiments thereof, it will be understood that those skilled in the art may make many changes and modifications without departing from the true spirit and scope of the invention, and accordingly, all such changes and modifications which fall within the true spirit and scope of this invention are intended to be covered in the appended claims. For example, the flexible reeds may each be formed of different materials or provided throughout their lengths with variable widths or thicknesses to exert a biasing force on the float to urge it in either a valve opening or closing position. Similarly, the valve seat can be contoured or oriented to provide this same effect. Also, additional valve ports may be provided for engagement by the balancing reeds 100 and 102, and if desired, the balancing reeds need not be disposed in planes parallel to one another or to the center reed. All of these possible modifications of the herein described embodiments of this invention are described in detail in the heretofore mentioned patents.

I claim:

1. Apparatus of the type comprising housing means defining a chamber and having an opening therein communicating with said chamber and having an internal valve seat portion facing into said chamber, a valve actuator movable in said chamber in a direction generally parallel to the plane of said valve seat portion, and a resilient strip member secured near one of its ends to said housing adjacent to said valve seat portion and near the other of its ends to the side of said actuator remote from said valve seat, said strip member being bent back upon itself to provide an intermediate portion of bowed shape extending across the top of said actuator, and said valve seat portion having an orifice therein positioned to be closed by said strip members when said actuator is in a first position and to be exposed when said actuator is in a second position.
2. Apparatus according to claim 1 wherein said actuator is a float assembly disposed in said chamber.
3. Apparatus according to claim 2 further comprising a plurality of additional resilient strip members each secured at one of its ends to the side of said housing opposite to said valve seat and at the other of its ends to said float assembly in close proximity to said valve seat, the intermediate portions of said additional strip members being bowed and extending across the top of said float assembly.
4. Apparatus according to claim 3 wherein the first of said strip members is positioned intermediate the other two of said strip members, said strip members being constructed such that the transverse force exerted on said float assembly by the first of said strip members is equal to the combined transverse forces exerted on said float assembly by the other two strip members.
5. A combination air eliminator and vacuum breaker comprising a housing having a float chamber therein, at least one liquid inlet and one gas outlet passageway communicating with said chamber through said housing, a float disposed in said chamber and adapted to rise and fall in response to changes in liquid level in said chamber, a valve seat surrounding said air outlet passageway, valve means including a resilient strip member secured at one end to said float and secured at the other

end to said housing adjacent to said valve seat, said ends being spaced apart by an intermediate portion which is free and maintained in bowed shape, said intermediate portion extending across the top of said float to an extent equal to at least one-half the corresponding dimension of said float, said strip member being bent back upon itself and being of sufficient length so as to form two generally opposed portions, one lying against said float and the other against said housing such that in one position of said float said member lies against said valve seat

to a predetermined extent and in another position of said float said strip member lies against said valve seat to a lesser extent.
